H. G. GILLMOR

RAIL ANCHOR

Filed Feb. 20, 1926

H. G. Gillmor
Inventor

UNITED STATES PATENT OFFICE.

HORATIO G. GILLMOR, OF WASHINGTON, DISTRICT OF COLUMBIA.

RAIL ANCHOR.

Application filed February 20, 1926. Serial No. 89,768.

My invention relates to anchoring devices for rails and more particularly to the one piece type of anchor in which an upwardly extending arm enters the fishing space and is wedged in between the head and base at one side of the rail and a shorter upwardly extending arm grips the rail base at the other side of the rail.

One of the objects of the invention is to provide a rail anchor of this general type which may be easily and efficiently manufactured, readily brought to its preliminary position for application on the rail; and, when applied to the rail will be in its proper operative position, firmly grip both the head and base of the rail and be so securely held in its operative position on the rail that it will not be accidentally dislodged or loosened but may, when desired, be quickly removed.

Other objects of the invention are to provide an anchor of the above general character in which the two upwardly extending arms are, during the application of the anchor to the rail, forced more widely apart than heretofore, with corresponding increase in the gripping pressure exerted on the rail by the resiliency of the anchor; to provide maximum gripping pressure upon the head of the rail near the edges of the head engaging end of the anchor; and to provide means for indicating the proper gripping position of the anchor on the rail.

The invention has for further objects such other new and improved arrangements and constructions as will be hereinafter described and claimed for carrying out the above stated objects.

The invention is illustrated in two embodiments in the accompanying drawings, wherein Figure 1 is an elevation, with the rail in section, of a rail anchor constructed in accordance with my invention in its operative position on the rail.

Figure 2 is a side elevation, with the cross tie in section, of the rail anchor illustrated in Figure 1 in its applied position.

Figure 3 is an elevation, with the rail in section, illustrating the passing of the rail anchor to its initial or preliminary position on the rail.

Figure 4 is an elevation, with the rail in section, of the anchor in its initial or preliminary position on the rail and before the anchor is subjected to any appreciable stress and

Figure 5 is an elevation, with the rail in sec-

tion, of a modified form of the rail anchor in its operative position on the rail.

In the drawing A indicates the head and B the base of a railroad rail and C one of the cross ties on which the rail is supported. The anchor is designated by D and is preferably formed of a steel bar bent to provide a long arm E, corresponding in shape roughly to the cross section of the ordinary fishbar or fishplate, and a shorter arm F. The long arm E is made to fit into the fishing space between the head and base of the rail and to be wedged therein and the short arm F is provided to engage and grip the rail base B at the side of the rail opposite to that engaged by the long arm E. The arms E and F are so formed and related to each other on the anchor D that, in the unstressed condition of the anchor, they are closer together than they are in the stressed condition of the anchor when it is in its applied operative position on the rail; so that they must be forced away the one from the other as the anchor D is forced from its initial or preliminary position shown in Figure 4 to its final operative position shown in Figure 1. The dotted lines in Figure 1 show the unstressed form and the full lines in the same figure the stressed form of the anchor D.

The end of the long arm E has its edges made thinner than its medial portion by forming depressions G, preferably by forging or pressing the material of the bar of which the anchor D is made, thus flattening the bar at its edges, forming slight projections I which extend beyond the face of the sheared end of the bar and at the same time leaving on the inside of the bar a portion narrower than the original width of the bar with an end surface H adapted to engage the under corner of the rail head, as illustrated in Figure 4.

The end of the shorter arm F is provided with means for determining the operative position of the anchor on the rail comprising surfaces K and L, preferably but not necessarily oblique to each other, formed by pressing or forging the stock of the bar of which the anchor D is formed. The forming of these surfaces flattens and at the same time broadens the end of the bar.

In applying anchors of this character to the rail the longer arm E must be brought to an inclined position in the fishing space between the head A and base B of the rail with the body underneath the rail base B so that the shorter arm F may be brought up by

the rail base B at the other side of the rail. This position is illustrated in Figure 3 and it will be seen that the distance which the two arms E and F may be apart in the unstressed condition of the anchor D is determined by the contact of one of the upper corners on the longer arm E with the web of the rail and the contact of one of the corners of the shorter arm F with the opposite edge of the rail base B. It is desirable to have the two arms E and F as close together as possible and still permit the anchor D to be brought to the initial position shown in Figure 4 because the extent to which the arms are spread apart as the anchor D is forced from its initial position to the final operative position determines the pressure exerted by the anchor D upon the rail when in its stressed condition in operative position on the rail. The forming of the depressions G on the upper end of the longer arm E with consequent narrowing of the inner face of the bar near its end permits the arm E to be brought closer to the web of the rail than would be the case if the depressions G were not provided. At the same time the forming of these depressions G widens the outer face of the bar at its end and forms the projecting portions I which extend above the plane of the surface of the end of the arm E but still retains inward from the projections I a surface H, below the projections I, which will engage the lower corner of the head A of the rail when the anchor is in its preliminary position on the rail as illustrated in Figure 4.

The flattening of the upper end of the shorter arm F further increases the distance between the upper corners of the two arms E and F, which determines the ability of the anchor D to be passed by the rail base B to the preliminary position shown in Figure 4, and thus, in connection with the depressions G at the upper end of the arm E, provides a construction in which the arms E and F are, in the unstressed condition of the anchor D, closer together than would otherwise be possible and the shorter arm thus may be made longer than would otherwise be possible.

To apply the anchor D to a rail it is, after passing the short arm by the rail base as illustrated in Figure 3, moved along the rail toward a tie, in the direction in which the rail tends to creep (indicated by the arrow in Figure 2), and then brought to the preliminary position shown in Figure 4 with the surface H on the upper end of the longer arm E engaging the under corner of the rail head A and the inner face of the shorter arm F engaging the upper corner at the other side of the rail base B.

The anchor D is then forced to the final operative position on the rail, as shown in Figures 1 and 2, by driving the longer arm E

into the fishing space between the head A and base B of the rail and by driving the shorter arm F downward by blows of a hammer as indicated by the arrow in Figure 4. This forcing of the anchor D into operative position spreads the arms E and F apart, the shorter arm F riding on the upper corner of the rail base B in the early stages of the movement, then the corner O riding on the vertical edge of the rail base until the surface L slips under and contacts with the lower corner of the rail base B at which time the surface K may contact with the vertical edge of the rail base, as shown in Figure 1, if the forging of the surface K has been such that its plane is vertical at this time. This is not essential. The providing of the two surfaces K and L has the advantage of indicating unfailingly to the person applying the anchor its correct operative position on the rail. The longer arm E, during this forcing of the anchor D to operative position, is wedged into the fishing opening between the head A and base B the surface H riding on the under side of the rail head A until the projections I come into engagement with the surface of the under side of the rail head A. The projections I in the final operative position of the anchor D bear upon the under surface of the rail head A, as shown in Figures 1 and 2, so that the pressure of the arm E on the head is greatest at the edges of the bar, of which the anchor D is formed.

In the modified form of the anchor D, shown in Figure 5, the projections I and the flattening G of the inner corners of the upper end of the arm E are formed by upsetting the end of the bar from which the anchor D is formed; and in flattening the end of the shorter arm F but one beveled surface M is provided. This form of the anchor is applied to the rail in the manner described above and in being forced from the initial to the final operative position, shown in Figure 5, the shorter arm F will ride on the upper corner of the rail during the early movement and then will ride with the corner P upon the vertical edge of the rail base and in the final operative position of the anchor D the lower corner of the rail base B will be engaged by the inclined surface M.

The direction in which the rail tends to creep is indicated by the arrow in Figure 2 and it will readily be understood that, with the longer arm E firmly wedged in between the head A and base B and there held by the pressure of the shorter arm F upon the rail base B at the other side of the rail, the contact of the anchor D with the tie C will prevent the forward or creeping movement of the rail.

Should it be desired to remove the anchor D from the rail, the shorter arm F is driven down by blows of a hammer in the direction of the arrows in Figures 1 and 5. The resi-

iciency of the anchor D permits the arm F to be driven down until its upper end reaches the lower corner of the rail base B and when this position is reached the anchor D will 5 spring off the rail. The pressure of the arm F against the rail base B is so great that the friction between the arm F and the rail base will retain the arm F in contact with the rail base B in any of the successive positions 10 reached in removing the anchor D from the rail and thus permit several blows of the hammer to effect the necessary downward movement of the arm F and the release of the anchor D from the rail by a continuation 15 of the movement of the anchor D on the rail necessary in bringing the anchor D to its operative position on the rail.

While I have described in the foregoing specification two forms of the rail anchor embodying my invention, I wish it understood that changes may be made in the details thereof without departing from the scope of the invention as defined by the appended 20 claims.

25 I claim:

1. A rail anchor comprising a bar formed to provide two terminal arms of unequal length, the longer engaging the head and upper surface of the base of a rail at one side 30 and having its head engaging end thinned at its edges by depressions at the inner corners thereof and the shorter engaging the rail base at the other side of the rail and a body, adapted to engage a tie, held out of contact 35 with the bottom of the rail base when the rail anchor is in operative position on the rail.

2. A rail anchor comprising a bar of metal formed to provide two arms, one of which is adapted to be wedged into the fishing space 40 between the head and base of a rail and has projections formed on the head engaging end thereof adjacent its transverse edges for engagement with the rail head and the other of which is adapted to engage the rail base at the other side, and a body, adapted to bear 45 against a cross tie, held out of contact with the bottom of the rail base when the anchor is in operative position on the rail.

3. A rail anchor comprising a bar formed 50 to provide two arms of unequal length, the longer arm having its upper end provided with projections adjacent the transverse edges of the bar adapted to engage the under side of the rail head when said anchor is in 55 operative position on the rail and also having a surface below and inwardly from said projections adapted to engage the lower corner of a rail head when said anchor is preliminarily positioned on the rail, and the 60 shorter arm adapted to engage the rail base opposite said longer arm, and a body adapted to engage a tie below and out of contact with the bottom of the rail base.

4. A rail anchor comprising a bar formed 65 to provide two arms of unequal length, the

longer arm being adapted to be wedged into the fishing opening between the head and base of a rail at one side and having its upper end flattened at the inner corners thereof to reduce the width of the inner face and increase the width of the outer face of said end and form projections adjacent the transverse edges of the end of the bar adapted to engage the under surface of the rail head, and the shorter arm being adapted to engage 70 the rail base at the other side of the rail, and a body adapted to bear against a tie but to be out of contact with the bottom of the rail base when the anchor is in operative 75 position on the rail.

5. A rail anchor comprising a bar formed to provide arms at the two ends thereof one arm being adapted to be wedged into the fishing space between the head and base of a rail at one side of the rail and the other arm being adapted to engage the base of the rail at the other side of the rail, the rail base engaging arm having at its upper end a formation adapted to extend above and below the lower corner of the rail base, and a body 80 adapted to engage a cross tie below and to be out of contact with the bottom of the rail base when said anchor is in operative position on the rail.

6. A rail anchor comprising a bar formed to provide two arms of unequal length, the longer being adapted to engage the under surface of the head and the upper surface of the base of a rail at one side of the rail and the shorter being flattened and provided 95 with two surfaces adapted to engage, when the anchor is in operative position on the rail, the vertical edge and lower corner of the rail base at the other side of the rail and a body adapted to engage a cross tie below and held out of contact with the bottom of the base of the rail.

7. A rail anchor comprising a bar bent to form two arms of unequal length the longer adapted to be wedged into the fishing space 100 at one side of a rail and the shorter provided with a surface adapted to engage the lower corner of the base of the rail, and a body adapted to engage a cross tie and to be out of contact with the rail base when the anchor 105 is in operative position on the rail.

8. A rail anchor comprising a bar formed to provide two arms of unequal length the shorter having two surfaces at an angle greater than a right angle the one to the other 110 engaging the lower corner and edge of a rail base and the longer engaging the head and upper surface of the rail base at the other side of the rail, and a body below and out of contact with the bottom of the rail base and adapted to engage a cross tie.

9. A rail anchor comprising a single bar of metal bent to form a body portion adapted to engage a cross tie but not the rail base, an arm at one end adapted to engage the lower 115

corner at least of the rail base at one side of the rail and an arm at the other end adapted to be wedged in between the head and base at the other side of the rail.

5 10. A rail anchor comprising a bar bent to form a body portion adapted to engage a cross tie but not the rail base, an arm having a portion adapted to be driven in between the

head and base of the rail at one side of the rail, and an arm having an end portion adapted to engage the rail base at the other side of the rail said end portion being provided with means for determining the operative position of the anchor on the rail. 10

H. G. GILLMOR.
